[57] **CLAIM**

The ornamental design for an inflatable, reflective solar evaporator, as shown and described.

DESCRIPTION

FIG. 1 is a front elevational view of an inflatable, reflective solar evaporator showing our new design, the undisclosed side being a mirror image of the side shown; FIG. 2 is a perspective view thereof as seen from the top and one side, with an exterior portion cut away to reveal interior details; and

FIG. 3 is a cross-sectional view thereof, on an enlarged scale, taken on line 3—3 of FIG. 2.

FIG. 1

FIG. 3
